UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

COMBINED STRIPPER AND THREAD-CUTTER FOR SEWING-MACHINES.

1,150,614.

Specification of Letters Patent. Patented Aug. 17, 1915.

Application filed October 28, 1913. Serial No. 797,779.

To all whom it may concern:

Be it known that I, JAMES R. MOFFATT, a citizen of the United States, residing at Chicago, in the county of Cook, State of Illinois, have invented certain new and useful Improvements in Combined Strippers and Thread-Cutters for Sewing-Machines, of which the following is a description, reference being had to the accompanying drawing and to the figures of reference marked thereon.

The invention relates to new and useful improvements in overseaming machines, and more particularly to an overseaming machine wherein the fabric is supported and fed to the stitching mechanism in substantially a vertical plane by intermittently rotating feed wheels.

An object of the invention is to provide means which will operate in connection with the feed wheels to strip the fabric from the feed wheels, so as to permit the free feed of the same through the machine.

A further object of the invention is to provide a thread cutter, which is located adjacent the stitching point, and which also assists in stripping the fabric from one of the feed wheels.

In the drawings which show by way of illustration one embodiment of the invention,—Figure 1 is a side view of a sewing machine of the above character, having my improvements applied thereto; Fig. 2 is a plan view of a portion of the same, showing the feed wheels, the strippers and thread cutter; Fig. 3 is a similar view showing the stripper fingers and cutter in plan; and Fig. 4 is a detail showing the combined thread cutter and stripper detached from the machine.

The machine as illustrated in the drawings, consists of a main casing 1, in which is mounted the main shaft and the operating mechanism for the stitch-forming elements. This main casing 1 carries a fixed bracket 2 in which is journaled a feed shaft carrying a feed wheel 3. Pivoted to the fixed bracket is a movable bracket 4 carrying a feed shaft having a feed wheel 5. Each of the feed wheels 3 and 5 is provided with a serrated or toothed section, which is adapted to clamp the fabric and feed the same. The fabric is supported in substantially a vertical plane with the upper edges

thereof projecting slightly above the feed 55 wheels. These feed wheels may be rotated by any suitable means. The outer bracket supporting the feed wheel 5 is yieldingly pressed toward the casing and, therefore, yieldingly moves the feed wheels into contact with the fabric.

A needle 6 reciprocates in a substantially horizontal plane above the feed wheels, and a looper 7 co-operates with the needle in forming an over-edge stitch.

The movable bracket 4 has an outwardly and upwardly projecting arm 8, which carries a needle guide 9. Also bolted to the arm 8 is a stripper plate 10. This stripper plate 10 is secured to the arm by suitable bolts 11. 70 The stripper plate is in the form of a finger which is curved on its inner face, substantially concentric to the curvature of the feed wheel 5, while its outer face is curved so as to lie eccentric to the curvature of the feed wheel. Outer curved surface of said fixed plate therefore crosses the periphery of the wheel. This curved stripping finger extends substantially to the stitching point and the inner end of the finger is underneath the 80 feed wheel. Said stripper finger at its outer end projects considerably beyond the feed wheel, so that as the fabric passes the stitching point, this stripper plate or finger will engage the fabric and crowd it out of the 85 teeth or serrations in the feed wheel.

Co-operating with the feed wheel 3 is a second stripper plate 12. This stripper plate is secured by suitable bolts or screws 13, to the main casing of the machine. Said 90 stripper plate extends underneath the feed wheel 3 and toward the stitching point. It is shaped in a general way similarly to the stripper plate 10, so its outer face will engage the fabric and crowd the same out of 95 the teeth or serrations in the feed wheel 3. Said stripper plate 12 is formed with a V-shaped notch 14, the edges of which are sharpened so as to form a thread cutter.

The fabric led between the feed wheels is 100 stripped from both of the feed wheels, so it is free therefrom, and when the end of the article is reached, a chain of stitches may be formed which connect the same to the next article to be stitched, and this chain of 105 stitches may be led into the thread cutter 14 and the articles severed from one another.

It is obvious that minor changes in the de-

tails of construction may be made, without departing from the spirit of the invention, as set forth in the appended claims.

Having thus described my invention, what I claim as new and desire to secure by Letters Patent, is:—

1. A sewing machine including in combination, coöperating feed wheels for supporting and feeding a fabric in substantially a vertical plane, a needle moving in a horizontal plane above the feed wheel, and means in rear of the needle in the direction of feed for stripping the fabric from each of said feed wheels.
- 15 2. A sewing machine including in combination, coöperating feed wheels for supporting and feeding a fabric in substantially a vertical plane, a needle moving in a horizontal plane above the feed wheel, a fixed plate extending to a point adjacent the needle and having a thread-cutting surface formed thereon.
- 25 3. A sewing machine including in combination, coöperating feed wheels for supporting and feeding a fabric in substantially a vertical plane, a needle moving in a horizontal plane above the feed wheel, a fixed plate extending to a point adjacent the needle and having a thread-cutting surface formed thereon, said fixed plate extending underneath said feed wheel and having a curved surface crossing the periphery there-

of for stripping the material from said feed wheel.

4. A sewing machine including in combination, coöperating feed wheels for supporting and feeding a fabric in substantially a vertical plane, a needle moving in a horizontal plane above the feed wheel, a fixed plate extending to a point adjacent the needle and having a thread-cutting surface formed thereon, said fixed plate extending underneath said feed wheel and having a curved surface crossing the periphery thereof for stripping the material from said feed wheel, and a stripper plate extending underneath the outer feed wheel and having its outer surface curved, so as to cross the periphery of said outer feed wheel and strip the fabric from said outer feed wheel.

5. A sewing machine including in combination, coöperating feed wheels for supporting and feeding a fabric in substantially a vertical plane, means including a plate for stripping the fabric from said feed wheels, said plate carrying means for cutting the thread.

In testimony whereof, I affix my signature, in the presence of two witnesses.

JAMES R. MOFFATT.
